UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

SLICING MACHINE

Application filed June 18, 1928, Serial No. 286,312, and in Great Britain June 21, 1927.

This invention relates to slicing machines of the kind in which the substance to be sliced is carried on a carriage which can be moved to and fro past a rotary knife, means being provided whereby the substance can be fed step by step towards the knife, either by hand or automatically, in the working of the machine.

Slicing machines of the above kind are generally operated either by hand or by an electric motor, but it has been proposed to make them convertible from hand-operated machines into power-driven machines, and vice versa. However, in order to do this, certain parts have to be added, removed or interchanged, and this entails time and trouble.

The object of this invention is to make slicing machines so that they can be readily operated by hand or by power as desired without the necessity for removing or changing any of the parts.

According to this invention, the slicing machine has, in combination, hand-operable mechanism and power-driven mechanism and also mechanism whereby, without altering or changing any of the parts, the machine can be operated wholly or partly by either the hand or the power mechanism, as desired, the arrangement being such that, when the machine is being driven by hand, it is disconnected from the power-driving mechanism.

With a machine constructed in accordance with the invention, the slicing knife and the substance supporting carriage can be operated in unison by the hand-operable mechanism or by the power-driving mechanism; the carriage can be hand-operated or may remain at rest while the knife is power-driven, and can be hand-operated while the knife remains at rest. The construction may be such that the carriage can be operated by power while the knife remains at rest.

In order that the invention may be clearly understood, two embodiments thereof, chosen by way of example, will now be described with reference to the accompanying drawing, in which:—

Fig. 1 is a diagrammatic elevation of one form of slicing machine embodying my invention;

Fig. 2 is a fragmentary view showing part of Fig. 1 in greater detail;

Fig. 3 is a fragmentary horizontal section of part of Fig. 1;

Fig. 4 is a diagrammatic fragmentary elevation of another form of slicing machine embodying my invention;

Fig. 5 is a plan view of Fig. 4; and

Fig. 6 is a view partly in elevation and partly in section.

Throughout the several figures, the same numerals of reference indicate the same or corresponding parts.

Referring to Figs. 1, 2 and 3, the slicing machine therein shown is of the well-known reciprocating carriage type, comprising a rotary knife 1 and a substance supporting carriage 2, adapted to be reciprocated along stationary guides 3 (one only being shown) past the knife. The machine is provided with an electric motor 4 and a hand-rotatable flywheel 5. The shaft of the motor 4 has a pulley 6 which is connected by a belt 7 with a pulley 8 on the knife shaft 9. The flywheel shaft 10 is connected with the carriage 2 through the intermediary of bevel gear-wheels 11, 12, a vertical crankshaft 13, a crank 14, and a connecting rod 15. A horizontal counter-shaft 16 has at one end a bevel gear-wheel 17 meshing with the gear-wheel 12 and at the other end a sprocket wheel 18 connected by a chain 19 with a sprocket wheel 20 on the knife shaft 9.

A free-wheel device 5' of any suitable construction, such for example as that shown in Fig. 2, is interposed between the pulley 8 and the knife shaft 9. In the device shown, the pulley 8 is mounted loosely on the shaft 9 and secured to the pulley 8 is a toothed wheel 22, which is disposed within the annular rim 20' of a circular casing 23, keyed to the shaft 9. The wheel 22 is formed, as shown, with wedge-shaped interdental spaces between teeth 21, each containing a ball 20. As will be obvious, the balls 24 provide a driving connection between the pulley 8 and the shaft 9 through the transmission of power from the wheel 22 to the rim 20' when the pulley is rotated clockwise, but not when the shaft is so rotated.

A manually controllable clutch of any suitable construction, such for example as that shown in Fig. 3, is interposed between the sprocket-wheel 18 and the counter-shaft 16. The clutch shown comprises a male element 25 and a female element 26 rigid with the sprocket wheel 18. The male element 25 is feathered to, but slidable on, the shaft 16, whereas the female element 26 is turnable, but not slidable, relatively thereto. The element 25 is urged towards the element 26 by a spring 28, but can be withdrawn at will from engagement with the element 26 by retracting a control rod 29, which is coupled through a bell-crank lever 30, having a forked arm 31, with the element 25. When the clutch elements are in inter-engagement, a driving connection is formed between the knife shaft and the counter-shaft, but, when they are disengaged, this driving connection is disestablished.

In the operation of the machine, when the motor is rotating, the knife will also rotate. When the clutch is engaged, the carriage will reciprocate, the machine being then wholly power-driven. When the clutch is disengaged, however, the carriage will not be reciprocated by power, but ordinarily will remain at rest. It may however be reciprocated by turning the flywheel 5.

When the motor is inoperative, the knife and carriage may be driven simultaneously by turning the flywheel, the clutch being in engagement. By withdrawing the clutch, and continuing to turn the flywheel, the carriage will reciprocate, but the knife will remain at rest.

It will be apparent that, when the machine as a whole is being operated by turning the flywheel, the motor will not rotate by virtue of the free-wheel device because the rim 20 when driven clockwise by the sprocket 20 and shaft 9 will merely urge the balls 20 towards the deeper portions of the recess in the wheel 22 where they will be inoperative to afford a driving connection between the rim 20 and the wheel 22.

Referring now to Figs. 4 to 6, the slicing machine therein partly shown is also of the reciprocatory carriage type. The carriage and the flywheel have not been shown, but the connections between these parts and the counter-shaft 16 is similar to those hereinbefore described with reference to, and as illustrated in, Fig. 1.

A sprocket wheel 40 and a pulley 41 are secured fast to an additional shaft 42 as best illustrated in Fig. 6. A sprocket wheel 43 and a pulley 44 are rigidly interconnected and are mounted on the shaft 42 in such manner as to be freely rotatable thereon. The two pulleys 41 and 44 constitute a fast and loose pulley unit having a driving connection through the belt 7 with the driving pulley 6 on the motor shaft. The driving pul-

ley 6 is diametrically small but axially long, and is connected through a free-wheel device 5', such as that shown in Fig. 2, to the motor shaft. The belt 7 is controlled by a belt shipper 49, which can be moved so as to cause the belt to wrap either the fast or the loose pulley, or to wrap both of them. The three positions of the belt shipper 49 are defined by notches 45 therein, with which notches a spring-pressed pawl co-operates, 75 the pawl being represented conventionally at 50. The loose sprocket wheel 43 is connected by a chain 46 to the sprocket wheel 18 on the counter-shaft 16, and the fast sprocket wheel 40 is connected by a chain 47 to the sprocket wheel 20 on the knife-shaft 9.

The operation of the machine, when the motor is running, is as follows:

When the belt 7 wraps the fast and the loose pulleys 41 and 44, both the knife shaft and the counter-shaft are rotated through their respective chain-and-sprocket drives, and, in consequence, the knife and the carriage are power-operated. When the belt wraps the fast pulley 41 and not the loose pulley 44, the knife rotates but the carriage remains at rest. If desired, however, the carriage may be reciprocated by hand. When the belt wraps the loose pulley 44 and not the fast pulley 41, the carriage is reciprocated, but the knife remains at rest.

The operation of the machine, when the motor is inoperative and the flywheel is turned manually, is as follows:

When the belt wraps the fast and loose pulleys both the knife and the carriage are operated. The rotation of the pulleys, however, will not be transmitted to the motor-shaft on account of the free-wheel between it and the pulley 6. When the belt wraps either the fast or the loose pulley, the carriage is reciprocated, but the knife remains at rest.

It should be noted that the several different operations which may be effected by the machine are selected by means of a single hand-member, viz. the belt-shipper 49. If desired, the handle by means of which the belt-shipper is shifted may be fitted with an electric switch 48 in circuit with the motor. This switch would serve as a convenient means of switching the motor on or off.

It will be apparent that the arrangement of the small driving pulley and relatively large driven pulley affords a speed-reduction device between the motor and the machine.

In either of the constructions hereinbefore described, a free-wheel device may be inserted between the fly-wheel shaft 10 and the bevel gear-wheel 11 thereon, the arrangement being such that, when the machine is driven by the power mechanism, the fly-wheel and its shaft remain at rest. In machines in which this free-wheel device is not

provided, the handle of the usual fly-wheel may be adapted for easy removal or to be turned down out of the way in order to avoid accidents when the machine is being motor driven.

5 As will be apparent, a slicing machine of either of the constructions herein described can be operated, at will, either by hand or by power without interfering with or altering in any way the component parts of the machine. On interrupting the operative connection between the knife and the reciprocating carriage, the knife can be motor-driven at a high speed, while the reciprocating carriage can be hand-operated, this being particularly advantageous as it allows the operator to regulate the rate of cutting when slicing certain kinds of meat, particularly such as may have pieces of bone in them. When the knife has to be sharpened or cleaned, the carriage may be maintained at rest while the knife is rotating. Moreover, the knife can be allowed to remain at rest while the carriage is hand-reciprocated, or, in the second construction herein described, is either hand-reciprocated, or power-reciprocated, past the stationary knife. This is especially advantageous for the slicing of cheese, bread and other soft substances, which have been found to become considerably distorted when cut by a rotating knife.

10 It is to be understood that modifications of the form of the invention herein described and illustrated may be made without departing from the scope of the invention.

I claim:—

1. In a slicing machine having a rotary slicing knife and a reciprocating carriage, the combination with motor driving mechanism for rotating said knife, a free-wheel connection in said driving mechanism preventing said driving mechanism from being driven by the rotation of said knife in one direction, driving mechanism between said knife and carriage, and a clutch interposed in said last-named driving mechanism.

15 2. In a slicing machine having a rotary slicing knife and a reciprocating carriage, the combination with motor driving mechanism for rotating said knife, a free-wheel connection in said driving mechanism preventing said driving mechanism from being driven by the rotation of said knife in one direction, driving mechanism between said knife and carriage, a clutch interposed in said last-named driving mechanism, and hand operated means for reciprocating said carriage and rotating said knife.

20 3. In a slicing machine, the combination with a carriage and a rotary slicing knife having relative bodily movement with respect to said carriage, of a driving motor, mechanism actuated by said motor for si-

multaneously rotating said knife and causing relative bodily movement between said knife and carriage, said mechanism including means for rotating said knife by said motor while said knife and carriage are relatively stationary with respect to their said bodily movement, said mechanism also including means for causing relative bodily movement between said knife and carriage while said knife is stationary with respect to its rotary movement.

25 4. In a slicing machine having a rotary knife and a reciprocating carriage, a driving motor, mechanism actuated by said motor for simultaneously rotating said knife and reciprocating said carriage, said mechanism including means for disconnecting said mechanism from said carriage to drive said knife alone while permitting manual reciprocation of said carriage, said mechanism also including means for disconnecting said mechanism from said knife to drive said carriage while said knife remains stationary.

30 5. In a slicing machine having a rotary knife and a reciprocating carriage, a driving motor, driving mechanism between said motor and knife, driving mechanism between said knife and carriage, manually operated driving means connected with said last-named driving mechanism, means for simultaneously driving said knife and carriage by said motor, means for separately driving said knife or carriage by said motor, means for simultaneously driving said carriage and knife by said manually operated driving means, and means for separately driving said carriage or knife by said manually operated driving means.

35 6. In a slicing machine having a rotary knife and a reciprocating carriage, the combination with a motor, and driving mechanism connected therewith for rotating said knife and reciprocating said carriage, hand operated means connected with said mechanism for reciprocating said carriage and rotating said knife, means in said mechanism for simultaneously and separately driving said knife and carriage by said motor and for simultaneously and separately driving said knife and carriage by said hand operated means, and means automatically preventing said motor from being driven when said slicing machine is driven by said hand operated means.

40 7. In a slicing machine having a rotary knife and a reciprocating carriage, a motor, driving mechanism between said motor and knife and between said knife and carriage, a free-wheel connection in said driving mechanism between said motor and knife, means included in said driving mechanism for simultaneously and separately driving said knife and carriage by said motor, and hand operated means connected with said driving

45 50 55 60 65 70 75 80 85 90 95 100 105 110 115 120 125 130

mechanism for simultaneously and separately driving said knife and carriage.

8. In a slicing machine having a rotary knife and a reciprocating carriage, the combination with a motor and driving mechanism connected therewith for rotating said knife and reciprocating said carriage, hand operated means connected with said mechanism for reciprocating said carriage and rotating said knife, and a fast and loose pulley mechanism for simultaneously and separately driving said knife and carriage by said motor and for simultaneously and separately driving said knife and carriage by said hand operated means.

9. In a slicing machine having a rotary knife and a reciprocating carriage, the combination with a motor and driving mechanism connected therewith for rotating said knife and reciprocating said carriage, hand operated mechanism connected with said driving mechanism for reciprocating said carriage and rotating said knife, means in said driving mechanism for simultaneously and separately driving said knife and carriage by said motor and for simultaneously and separately driving said knife and carriage by said hand operated mechanism, and a single manually operated member for controlling said means.

10. In a slicing machine having a rotary knife and a reciprocating carriage, the combination with a motor and driving mechanism connected therewith for rotating said knife and reciprocating said carriage, hand operated means connected with said mechanism for reciprocating said carriage and rotating said knife, and a fast and loose pulley mechanism for simultaneously and separately driving said knife and carriage by said motor and for simultaneously and separately driving said knife and carriage by said hand operated means, and a single manually operated member for controlling said fast and loose pulley mechanism.

11. In a slicing machine having a rotary knife and a reciprocating carriage, the combination with a motor and driving mechanism connected therewith for rotating said knife and reciprocating said carriage, fast and loose pulley mechanism in said driving mechanism for simultaneously and separately driving said knife and carriage.

12. In a slicing machine having a rotary knife and a reciprocating carriage, the combination with a motor and driving mechanism connected therewith for rotating said knife and reciprocating said carriage, a fast and loose pulley in said driving mechanism, a belt for driving said pulleys from said motor, said carriage being driven through one of said pulleys and said knife being driven by the other of said pulleys, and means for shifting said belt from one pulley to the other and to an intermediate position for driving both pulleys simultaneously.

13. In a slicing machine having a rotary knife and a reciprocating carriage, the combination with a motor for driving said knife and carriage, a spindle, fast and loose pulleys on said spindle, a belt driven by said motor, means for shifting said belt to selectively engage either or both of said pulleys, driving mechanism connecting one of said pulleys with said reciprocating carriage, driving mechanism connecting the other of said pulleys with said knife, and hand operated driving means connecting said first-mentioned driving mechanism for manually rotating said knife and reciprocating carriage.

14. In a slicing machine having a rotary knife and a reciprocating carriage, the combination with a motor and driving mechanism connected therewith for rotating said knife and reciprocating said carriage, a fast and loose pulley in said driving mechanism, a belt for driving said pulleys from said motor, said carriage being driven through one of said pulleys and said knife being driven by the other of said pulleys, means for shifting said belt from one pulley to the other and to an intermediate position for driving both pulleys simultaneously, and a free-wheel connection between said pulleys and motor.

15. In a slicing machine having a rotary knife and a reciprocating carriage, the combination with a motor and driving mechanism connected therewith for rotating said knife and reciprocating said carriage, a fast and a loose pulley in said driving mechanism, a belt for driving said pulleys from said motor, said carriage being driven through one of said pulleys and said knife being driven by the other of said pulleys, a member for shifting said belt from one pulley to the other and to an intermediate position connecting both pulleys, and a switch on said member for controlling said motor.

16. In a slicing machine having a rotary knife and a reciprocating carriage, a shaft having a crank and connection rod connection with said carriage, a gear on said shaft, a second gear driven by a hand operated fly-wheel meshing with said first-named gear, a gear having a sprocket at one end meshing with said first-named gear, a spindle having fast and loose pulleys thereon, a sprocket on one of said pulleys meshing with said first-named sprocket, a driving connection extending between the other of said pulleys and said knife, a motor having flexible driving means for rotating said pulleys, and means for shifting said flexible driving means from one pulley to the other and to an intermediate point connecting both pulleys for simultaneous rotation thereof.

17. A slicing machine comprising a rotary slicing knife, a reciprocating carriage, a motor having mechanism connected therewith for rotating said knife, a free-wheel

connection in said driving mechanism for preventing said mechanism from being driven by the rotation of said knife in one direction, driving mechanism between said 5 knife and carriage, and a clutch interposed in said last-named driving mechanism, said free-wheel comprising a pair of relatively movable members rotatable about an axis concentric with the axis of rotation of said 10 knife, said members having opposed faces inclined toward each other so that said faces are closer together at one position therealong than at another position, and a member interposed between said faces of greater thickness 15 than the shortest distance between said faces and of less thickness than the greatest distance between said faces.

In testimony whereof I have signed my name to this specification on this 31st day of 20 May, A. D. 1928.

CORNELIS F. M. VAN BERKEL.
